UNITED STATES PATENT OFFICE.

MICHAEL McNAMEE, OF BALTIMORE, MARYLAND.

LAMP.

SPECIFICATION forming part of Letters Patent No. 245,535, dated August 9, 1881.

Application filed May 31, 1881. (No model.)

To all whom it may concern:

Be it known that I, MICHAEL McNAMEE, a citizen of the United States of America, residing at Baltimore, in the county of Baltimore 5 and State of Maryland, have invented certain new and useful Improvements in Lamps; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention relates to certain improvements in lamps, which are hereinafter first described, and then designated in the claims.

In the drawings hereto annexed, Figure 1 is 20 a perspective of a wall-lamp embodying my improvements. Fig. 2 is a side view of a vertical section of the same lamp. Fig. 3 illustrates the flame-guard and wick-support. Fig. 4 is a section of the filler-indicator on a larger scale. Fig. 5 shows the application of the 25 indicator to an ordinary hand-lamp.

The letter A designates the oil-fount, B the filling-orifice closed by the usual screw-cap, and C the indicator.

The letter d denotes the back plate or hanger, 30 by which the wall-lamp is suspended.

One of the features of my invention consists of the peculiar filler-indicator for lamps whose oil-founts are made of metal. A cylinder, E, has its lower end open, and its upper end 35 rounded, as at f, in the form of a half-sphere.

An opening in the center of this rounded part permits a glass tube, C, to fit loosely. The tube is flanged at both ends, and plays up and down through the opening. After one end of 40 the tube is flanged the other is inserted through the opening in the rounded part, and is then flanged by a suitable tool and blow-pipe. In practice about three-eighths of an inch is a proper length for the glass tube. A hollow 45 glass ball, g, fits loosely in the cylinder E, the lower end of which has an inward-turned flange, h, which so contracts the bottom opening as to prevent the ball from dropping out. This ball serves as a float, for which the cylinder 50 acts as a guide. An opening in the top of the

metal oil-fount permits the cylinder to be secured in such position that only the rounded end or half-sphere f will project above the top of the oil-fount, as shown in the drawings. The sides of the cylinder next to or adjoining 55 the top have perforations i to afford vent when the oil has risen above the lower end of the cylinder in filling. The oil is entered through the opening B, and the hollow glass ball-float rises until the fount is nearly filled, at which 60 time the ball presses against the lower end of the glass-tube indicator and raises it until one-half of the ball occupies the concave socket formed by the rounded part f. As the glass-tube indicator is not connected with the ball-float there is no movement of the indicator as 65 the float rises until the lamp-fount is very nearly full. The indicator, being tubular, serves to vent the lamp, and when filling the fount with oil it allows the escape therefrom of the air. 70 In the case of the wall-lamp it serves a special use by venting to allow the oil to flow through the supply-tube to the wick-tube, which parts are hereinafter described. When the fount is full the ball-float presses against the flanged 75 and concaved end of the tube indicator, and thus closes the vent.

This indicator is applicable to any style of metal lamp, such as street or hand lamps, as 80 shown in Fig. 5.

Another feature of my invention will now be described.

L designates a wick-cup, consisting of a tube secured on the outside of the oil-fount. The lower end of this wick-tube is below the bottom 85 or lowest part of the oil-fount, with which the wick-tube is connected by a short and small supply-tube, n, so placed as to drain the fount. The upper end of the wick-tube is provided with an ordinary threaded lamp collar or ring, 90 m, into which any suitable burner (not shown) may be screwed. Just above the supply-tube n is a funnel-shaped interceptor, p, perforated to allow the oil to rise into the tube L. This interceptor sustains the end of the wick, keeping it out of the sediment which collects in the chamber at the bottom of the tube at g, that being the lowest place in the lamp for oil. This arrangement prevents any accumulation of sediment in such position as to en- 95 100

danger choking up the small supply-tube. It will be seen that the top of the interceptor is above the supply-tube, where it rests upon the inward shoulder, r , while the lower funnel-shaped end depends to a point below the mouth of the supply-tube, which it serves to guard, whereby all the oil may be consumed out of the fount without danger at that time of flame entering the fount by way of the wick-tube, and the shape and position of the interceptor serve to keep the wick from the sediment in the bottom q of the tube. The lower end of the wick-tube serves, in connection with the lower edge of the back d' of the lamp, as a foot for the lamp when not hanging against the wall.

Having described my invention, I claim and desire to secure by Letters Patent of the United States—

1. The combination of an oil-fount having an opening in the top, a glass tube to fit loosely in the opening, and having a flange at both ends, and a float to move the glass tube, as set forth.

2. In a filler-indicator, the combination of a cylinder having its upper end rounded in the form of a half-sphere, and provided with an opening, a tube to fit loosely in the opening, and a ball-float fitting loosely in the cylinder, as set forth.

3. In a lamp, the combination of an oil-fount, a wick-tube secured on the outside of the oil-fount, an oil-supply tube, one end of which connects with the oil-fount and the other end with the wick-tube at a point above its bottom, a funnel-shaped interceptor in the wick-tube, having its top edge above the orifice of the oil-supply tube and its lower end below the orifice, and a sediment-chamber in the bottom of the wick-tube and below the interceptor, as set forth.

In testimony whereof I affix my signature in presence of two witnesses.

MICHAEL McNAMEE.
